(57) **CLAIM**

The ornamental design for a fish-shaped base for a fly tying vise, as shown and described.

DESCRIPTION

FIG. 1 is a perspective view of the fish-shaped base of the present invention;

FIG. 2 is a front view thereof;

FIG. 3 is a top plan view thereof;

FIG. 4 is a rear view thereof;

FIG. 5 is side elevational view thereof;

FIG. 6 is bottom plan view thereof; and,

FIG. 7 is an inverse side elevational view thereof.

The broken line showing the fly tying vise and arm support therefor in FIG. 1 is illustrative of environmental structure only and forms no part of the claimed design.
